FUNGICIDAL QUATERNARY AMMONIUM SALTS
OF DITHIOCARBAMIC ACIDS

liability company of the Netherlands

No Drawing. Filed May 20, 1959, Ser. No. 814,407

6 Claims. (Cl. 167—22)

This invention relates to fungicidal compositions and processes which employ quaternary ammonium salts of substituted dithiocarbamic acids and of ethylenebisdithiocarbamic acid.

Fungi infections of plants have in the past been minimized or prevented by application to the plants of sodium, zinc, iron and other such salts of dithiocarbamic acids and similar salts of the ethylenebisdithiocarbamic acid. These materials, however, will not control a fungus infection which has become well established.

Mercurial fungicides have been used for the control of established fungi infection but such mercurials are too toxic to be entirely satisfactory.

According to the present invention, the fungicidal compounds employed are, speaking generally, quaternary ammonium salts of dithiocarbamic acid. These compounds may be applied to the objects or articles to be protected against fungi in any conventional manner.

They are preferably applied together with a carrier for the compound. The carrier may be a filler or alternatively the compound may be dissolved in solvents to which there may be added desirable binders, wetting agents, emulsifiers, dispersing agents, etc.

Dithiocarbamates which can be used in compositions and processes of the invention have the following formula:

(1)

in which:

Q is

or

R₁ is an aliphatic hydrocarbon group of 10 to 18 carbons. R₂ is hydrogen or an aliphatic hydrocarbon group of less than 5 carbons.

R₃ is an aliphatic hydrocarbon group of less than 5 carbons.

R₄ is an aliphatic or aralkyl hydrocarbon group of less than 13 carbons.

R₅ is methyl or ethyl.

R₆ is methyl or ethyl, or R₄, R₅ and R₆ taken together with the nitrogen atom form the pyridinium group.

While any of the dithiocarbamates above shown can be employed, by far the best results for the purposes of the present invention are obtained using those of Formula 1 in which

Q is $-\text{N}(\text{CH}_3)_2$

and in which R₄, R₅ and R₆ taken together with the nitrogen atom form the pyridinium group.

2

A preferred scope of the invention may instead be stated by saying that according to the preferred form of the invention, the quaternary ammonium radical of the novel compound has a higher alkyl group attached to the nitrogen atom, the remaining radicals attached to the nitrogen atom being alkyl and/or aralkyl. Of course, when the quaternary ammonium radical is pyridinium, three of the positions of the nitrogen atom constitute part of the pyridine ring. Higher alkyl includes alkyl radicals containing more than 8 carbon atoms and generally between 8 and 20 carbon atoms. Preferably, according to the present invention, the higher alkyl group contains between 11 and 19 carbon atoms.

The dithiocarbamic acid is preferably an alkylidithiocarbamic acid and more preferably a lower alkylidithiocarbamic acid such as dimethyldithiocarbamic acid, methylidithiocarbamic acid, diethyldithiocarbamic acid and ethylenebisdithiocarbamic acid.

The compounds as above described are extremely effective as fungicides against plant pathogenic fungi and afford the valuable and unique effect of controlling such fungi even many hours after the incidence of infection. Often it is impossible to spray plants before the fungus infection occurs and, particularly in rainy periods, it is impossible to spray soon enough after infection to control the disease. The compositions and methods of the present invention provide a way of controlling such plant pathogenic fungi long after they would be past control by non-mercurial fungicides heretofore available.

The compositions and processes of the invention are especially valuable for the control of fungi which infect trees such as fruit-bearing trees. Control of such fungi can be obtained up to three days after infection.

If desired, the composition which is used to treat the plants may include, in addition to a compound or compounds of the present invention, other fungicides, insecticides, and/or other agents for controlling noxious organisms.

The compounds employed according to the present invention are preferably prepared by a double conversion of a soluble quaternary ammonium salt, such as chloride, with a soluble salt of a dithiocarbamic acid, such as a sodium salt.

Thus, a quaternary ammonium chloride is reacted with an equimolecular amount of an appropriate alkali metal dithiocarbamate in water to produce a precipitate. This precipitate will contain impurities such as the halide salt of the alkali metal and ordinarily the crude mixture thus obtained will be used as such in the composition and processes of the present invention. Alternatively, the quaternary ammonium dithiocarbamate can be further purified to separate it from the salt and any other impurities.

In like manner, two molecular equivalents of an appropriate quaternary ammonium halide can be reacted with one molecular equivalent of disodium ethylenebisdithiocarbamate, or another alkali metal ethylenebisdithiocarbamate, in water to produce a precipitate. This can be used as such or the dithiocarbamate portion can be purified if desired.

Example 1

85 g. of cetylpyridinium chloride (0.25 mol) were dissolved in 600 ml. of water to which were added, while stirring, 36 g. sodium dimethyldithiocarbamate (0.252 mol), dissolved in 180 ml. of water. 100 g. of a pale-brown colored product (cetylpyridinium dimethyldithiocarbamate) were separated from the reaction mixture.

The fungicidal activity of this product was tested according to the slide germination method of evaluating fungicides (Phytopathology, 33, 627-632) with regard to the fungi *Clasterosporium carpophilum* and *Fusarium*

3

solani. The LD-50 was found to 0.1 and 1.4 p.p.m. respectively. The test was repeated using sodium dimethyldithiocarbamate which showed an LD-50 of 4 and 20 p.p.m. respectively. In a similar manner the following quaternary ammonium salts were prepared and their LD-50 with regard to *Clasterosporium carpophilum* and *Fusarium solani* were evaluated.

Example 2

Reaction of sodium dimethyldithiocarbamate with 10
cetyl pyridinium bromide to produce cetyl pyridinium
dimethyldithiocarbamate.

Cetyl pyridinium bromide (38.4 grams, 0.1 mole) is dissolved in warm water to give a 20% solution at 55° C. This solution is added over a 20-minute period, with stirring, to a solution of sodium dimethyldithiocarbamate (14.3 grams, 0.1 mole) in 130 ml. water. A viscous brown solution forms which upon cooling to 5° C. forms a very thick slurry. The product is isolated by filtering, reslurrying in ice water, filtering and drying at room temperature. It is a brownish orange waxy solid, melting at 56-61° C., and is sufficiently pure for fungicidal application. The small amounts of water and bromide ion contained in this material may be removed by conventional means. For example, the water may be removed by vacuum drying at elevated temperatures, and the bromide ion can be removed by recrystallization or chromatography over alumina, using chloroform as bath solvent and eluent. The purified product melts at 64.5-68.5° C.

Further examples of quaternary ammonium dithiocarbamates which can be used in compositions and process of the invention are as follows:

Reaction product of sodium dimethyldithiocarbamate with:

22. Cetyl pyridinium chloride to make cetyl pyridinium dimethyldithiocarbamate
23. Cetyl pyridinium bromide to make cetyl pyridinium dimethyldithiocarbamate
24. Tetradecyl pyridinium chloride to make tetradecyl pyridinium dimethyldithiocarbamate

4

25. Cetyl trimethyl ammonium bromide to make cetyl trimethyl ammonium dimethyldithiocarbamate

26. Decyl isobutyl dimethyl ammonium bromide to make decyl isobutyl dimethyl ammonium dimethyl dithiocarbamate

27. Tetradecyl triethyl ammonium chloride to make tetradecyl triethyl ammonium dimethyldithiocarbamate

28. Stearyl pyridinium chloride to make stearyl pyridinium dimethyldithiocarbamate

29. Dodecyl pyridinium bromide to make dodecyl pyridinium dimethyldithiocarbamate

30. Stearyl triethyl ammonium chloride to make stearyl triethyl ammonium dimethyldithiocarbamate

31. Undecyl pyridinium chloride to make undecyl pyridinium dimethyldithiocarbamate

Reaction product of sodium diethyldithiocarbamate with:

32. Cetyl pyridinium bromide to make cetyl pyridinium diethyldithiocarbamate

33. Dodecyl pyridinium bromide to make dodecyl pyridinium diethyldithiocarbamate

34. Stearyl benzyl dimethyl ammonium chloride to make stearyl benzyl dimethyl ammonium diethyldithiocarbamate

35. Stearyl pyridinium chloride to make stearyl pyridinium diethyldithiocarbamate

36. Cetyl triethyl ammonium chloride to make cetyl triethyl ammonium diethyldithiocarbamate

37. Tetradecyl trimethyl ammonium chloride to make tetradecyl trimethyl ammonium diethyldithiocarbamate

38. Decyl dimethyl benzyl ammonium bromide to make decyl dimethyl benzyl ammonium diethyldithiocarbamate

39. Dodecyl triethyl ammonium chloride to make dodecyl triethyl ammonium diethyldithiocarbamate

Reaction product of sodium di-n-butylthiocarbamate with:

40. Cetyl pyridinium chloride to make cetyl pyridinium di-n-butylthiocarbamate

41. Tetradecyl trimethyl ammonium chloride to make tetradecyl trimethyl ammonium di-n-butylthiocarbamate

42. Cetyl trimethyl ammonium bromide to make cetyl trimethyl ammonium di-n-butylthiocarbamate

43. Stearyl dimethyl benzyl ammonium chloride to make stearyl dimethyl benzyl ammonium di-n-butylthiocarbamate

44. Cetyl dimethyl benzyl ammonium chloride to make cetyl dimethyl benzyl ammonium di-n-butylthiocarbamate

45. Dodecyl trimethyl ammonium bromide to make dodecyl trimethyl ammonium di-n-butylthiocarbamate

46. Dodecyl dimethyl benzyl ammonium chloride to make dodecyl dimethyl benzyl ammonium di-n-butylthiocarbamate

47. Tetradecyl triethyl ammonium chloride to make tetradecyl triethyl ammonium di-n-butylthiocarbamate

48. Stearyl trimethyl ammonium bromide to make stearyl trimethyl ammonium di-n-butylthiocarbamate

49. Decyl isopropyl dimethyl ammonium chloride to make decyl isopropyl dimethyl ammonium di-n-butylthiocarbamate

Reaction product of disodium ethylenedithiocarbamate with:

50. Cetyl pyridinium bromide to make cetyl pyridinium ethylenedithiocarbamate

51. Tetradecyl triethyl ammonium chloride to make tetradecyl triethyl ammonium ethylenebisdithiocarbamate
52. Tetradecyl pyridinium chloride to make tetradecyl pyridinium ethylenebisdithiocarbamate
53. Stearyl pyridinium chloride to make stearyl pyridinium ethylenebisdithiocarbamate
54. Cetyl trimethyl ammonium chloride to make cetyl trimethyl ammonium ethylenebisdithiocarbamate
55. Stearyl n-butyl diethyl ammonium chloride to make stearyl n-butyl diethyl ammonium ethylenebisdithiocarbamate
56. Dodecyl trimethyl ammonium bromide to make dodecyl trimethyl ammonium ethylenebisdithiocarbamate
57. Stearyl trimethyl ammonium chloride to make stearyl trimethyl ammonium ethylenebisdithiocarbamate
58. Decyl triethyl ammonium chloride to make decyl triethyl ammonium ethylenebisdithiocarbamate
59. Undecyl trimethyl ammonium chloride to make undecyl trimethyl ammonium ethylenebisdithiocarbamate
60. Stearyl triethyl ammonium chloride to make stearyl triethyl ammonium ethylenebisdithiocarbamate
61. Stearyl benzyl diethyl ammonium chloride to make stearyl benzyl diethyl ammonium ethylenebisdithiocarbamate

Reaction product of sodium di-n-propyldithiocarbamate with:

62. Cetyl pyridinium bromide to make cetyl pyridinium di-n-propyldithiocarbamate
63. Stearyl trimethyl ammonium chloride to make stearyl trimethyl ammonium di-n-propyldithiocarbamate

Reaction product of sodium N-methyl-N-ethyldithiocarbamate with:

64. Cetyl pyridinium chloride to make cetyl pyridinium N-methyl-N-ethyldithiocarbamate
65. Dodecyl benzyl diethyl ammonium chloride to make dodecyl benzyl diethyl ammonium N-methyl-N-ethylenedithiocarbamate

Reaction product of sodium N-methyl-N-isopropyldithiocarbamate with:

66. Cetyl trimethyl ammonium chloride to make cetyl trimethyl ammonium N-methyl-N-isopropyldithiocarbamate
67. Tetradecyl dimethyl benzyl ammonium chloride to make tetradecyl dimethyl benzyl ammonium N-methyl-N-isopropyldithiocarbamate

Reaction product of sodium N-methyl-N-(n-butyl)dithiocarbamate with:

68. Dodecyl methyl diethyl ammonium chloride to make dodecyl methyl diethyl ammonium N-methyl-N-(n-butyl)dithiocarbamate
69. Stearyl pyridinium chloride to make stearyl pyridinium N-methyl-N-(n-butyl) dithiocarbamate

Reaction product of sodium N-ethyl-N-(n-propyl)dithiocarbamate with:

70. Stearyl decyl dimethyl ammonium chloride to make stearyl decyl dimethyl ammonium N-ethyl-N-(n-propyl)dithiocarbamate

Reaction product of sodium N-ethyl-N-isobutyldithiocarbamate with:

71. Tetradecylpyridinium chloride to make tetradecyl pyridinium N-ethyl-N-isobutyldithiocarbamate

Reaction product of sodium N-(n-propyl)-N-(n-butyl)-dithiocarbamate with:

72. Cetyl benzyl dimethyl ammonium chloride to make cetyl benzyl dimethyl N-(n-propyl)-N-(n-butyl)dithiocarbamate

73. Cetyl pyridinium bromide to make cetyl pyridinium N-(n-propyl)-N-(n-butyl)dithiocarbamate

Reaction product of sodium ethyldithiocarbamate with:

74. Cetyl pyridinium bromide to make cetyl pyridinium ethyldithiocarbamate
75. Cetyl dimethyl benzyl ammonium chloride to make cetyl dimethyl benzyl ammonium ethyldithiocarbamate

Reaction product of sodium n-propyldithiocarbamate with:

76. Tetradecyl trimethyl ammonium chloride to make tetradecyl trimethyl ammonium n-propyldithiocarbamate

77. Decyl triethyl ammonium bromide to make decyl triethyl ammonium n-propyldithiocarbamate

Reaction product of sodium n-butylidithiocarbamate with:

78. Cetyl pyridinium chloride to make cetyl pyridinium n-butylidithiocarbamate

79. Dodecyl dimethyl benzyl ammonium chloride to make dodecyl dimethyl benzyl ammonium n-butylidithiocarbamate

The appropriate quaternary ammonium halide was in each instance reacted with the dithiocarbamate as set out in Examples 1 and 2 above. Thus, in each instance, equimolecular amounts of the reactants are dissolved in water and reacted to form a precipitate.

Fungicidal compositions of the present invention containing at least one of the quaternary ammonium products as above described can be prepared by admixing one or more of these products with pest control adjuvants or modifiers to provide compositions in the form of water-dispersible powders, dusts, solutions, and emulsifiable solutions.

While the quaternary ammonium dithiocarbamates employed in compositions of the invention can be formulated in any conventional manner and used in processes of the invention for the control of fungi, it is much preferred that they be formulated in compositions which contain a free-flowing, inert powder. Still more preferred are such mixtures in which one or more surfactants are present.

The free-flowing, inert powders can be any of the extenders commonly employed in the insecticide, herbicide and fungicide art for the application of such materials and may include natural clays such as attapulgite and kaolinite clays, diatomaceous earth, talcs, synthetic mineral fillers derived from silica and silicate such as synthetic fine silica and synthetic calcium or magnesium silicate, wood flour and walnut shell flour.

The amount of the extenders can vary widely and can range from about 10 to 95% by weight of a fungicidal composition. Thus the amount of dithiocarbamate will range from about 5 to 90%. The particle size can vary considerably but will ordinarily be somewhat under 50 microns in the finished formulation. As a matter of convenience, the compositions can be prepared with a pulverulent extender or with an extender with particles above the desired size and after admixture with the quaternary ammonium dithiocarbamate the entire composition can be suitably ground so that the particle size of the extender will be small enough to give free-flowing compositions which can readily be applied. Particle size will usually run something under 50 microns in such finished products.

Compositions as described can, in addition to the finely divided extender, contain a surfactant. The surfactant can be a dispersant, a de-foamer or an emulsifying agent which will assist dispersion of the composition in the water. The surfactants or "surface-active agents" can include such cationic and non-ionic surface-active agents as have heretofore been generally employed in pest control compositions of similar type. Suitable surface-active agents are set out, for example, in Searle U.S. Patent 2,426,417, Todd U.S. Patent 2,655,447, Jones U.S. Patent 2,412,510, or Lenher U.S. Patent 2,139,276. A detailed list of such agents is set forth by J. W. McCutcheon in "Soap and Chemical Specialties," December 1957, Janu-

ary, February, March and April 1958. See also McCutcheon in "Chemical Industries," November 1947, page 8011 et seq., entitled "Synthetic Detergents"; and Bulletin E-607 of the Bureau of Entomology and Plant Quarantine of the U.S. Dept. of Agriculture. In general, anionic surface-active agents cannot be used.

Suitable surfactants for use in compositions of the present invention are alkyl and alkyl aryl polyether alcohols, polyoxyethylene sorbitol or sorbitan fatty acid esters, polyethylene glycol fatty esters and fatty alkylol amide condensates.

In general, less than about 10% by weight of the surface-active agent will be used in compositions of the invention and ordinarily the amount of surface-active agent will be less than 1% by weight. Usually, in accordance with customary practices, the amount will range from about 0.5 to 2% of a surface-active agent.

Particularly preferred surface-active agents include polyvinyl alcohol, methocel, gum arabic, long chain amine acetates, substituted oxazolines and alkyl dimethyl-amine oxides.

The quaternary ammonium dithiocarbamates used in compositions of the invention are very slightly water soluble and are cationic in nature, thus, to greater or lesser extents, various of the compounds above described act as wetting and dispersing agents. This action, however, will often be insufficient and a suitable non-ionic or cationic dispersant should also be added.

While formulations containing free-flowing, finely divided extenders and with or without an added wetting agent are much preferred compositions of the invention, it will be understood that the quaternary ammonium compounds can be used in processes of the invention by formulation and application in various conventional manners.

Thus, the compounds though only slightly soluble can be dissolved in water at the point of use to obtain enough of the active material to obtain control of fungi.

The quaternary ammonium compounds to be used in the processes of the invention can also be dissolved in appropriate non-phytotoxic organic solvents. A concentrate thus formed can be mixed with water, using a dispersing agent if one is necessary. This cetylpyridinium dimethyldithiocarbamate can be dissolved to form a concentrated solution in dimethylformamide and this can be mixed with an appropriate quantity of water to obtain the concentration of the dithiocarbamate desired. Other suitable solvents are lower molecular weight aromatic hydrocarbons, usually benzene, toluene, xylene and alkylated naphthalene, volatile, low molecular weight esters, and water immiscible ketones such as ethyl to amyl acetate and methylisobutyl ketone to dibutyl ketone.

Emulsifiable oils can be prepared in the same fashion using an oil in which the dithiocarbamate is soluble, such as xylene. Such emulsifiable oils can contain other suitable solvents for the quaternary ammonium dithiocarbamates as above. With such oils, suitable surfactants should be used such as cationic or non-ionic agents known to the art as emulsifying agents as above described.

In the application of quaternary ammonium dithiocarbamates according to the invention, fungicidal control is obtained by applying the active compound at a dosage, or at a rate, from about 0.05 to 5 pounds per acre. The optimum amount in each instance is largely dependent upon the exact method of application, the state and condition of growth of plants to be treated, the climatic conditions and other such well-understood variables.

As will be shown later in the examples and has been indicated generally above, the quaternary ammonium compounds employed according to the invention are effective for the control of such fungus diseases as apple scab, pear scab, peach scab, cedar-apple rust, cherry leaf spot, Brooks spot, sooty blotch, bitter rot, black rot, black spot (of roses) and apple blotch.

A fungicidal composition was prepared by mixing 20 parts by weight of cetylpyridinium dimethyldithiocarbamate with 70 parts by weight of a filler (fuller's earth) and 10 parts by weight of dispersing agent (refined sulfite lye powder). This composition is identified as composition A in Tests I and II below and is sprayed in the form of a suspension containing 0.2% of composition A.

The above composition was compared with composition Z containing 80% of zinc dimethyldithiocarbamate in two tests for controlling *Venturia inaequalis* (apple scab) on the James Grieve variety. The results were as follows:

Test I.—The trees were sprayed 24 hours after infection of the leaf. After spraying 20 days elapsed before the percentage of leaf surface affected by scab was determined.

	Treatment of tree	Average percent of leaf surface affected by scab
Non-treated.....		54
Composition Z, 0.1%.....		20.7
Composition A, 0.2%.....		1.4

Test II.—The trees were sprayed as in Test I but this time 48 hours after infection of the leaf. After spraying 19 days elapsed before the percentage of leaf surface affected by scab was determined.

	Treatment of tree	Average percent of leaf surface affected by scab
Non-treated.....		13.6
Composition Z, 0.1%.....		3.6
Composition A, 0.2%.....		0.2

Example 81

	Percent
Cetyl pyridinium dimethyldithiocarbamate	20
Attapulgite clay	80

The above composition is prepared by blending the components together and passing through a micropulverizer until substantially all agglomerates are broken down to 50 microns or smaller.

This formulation is applied at the rate of 2 pounds per 100 gallons of water to an apple orchard 48 hours after a scab infection period. Excellent curative action on the scab infection is obtained and the trees are protected from re-infection by the disease.

Example 82

	Percent
Cetyl trimethylammonium dimethyldithiocarbamate	50
Low viscosity polyvinyl alcohol	1
Synthetic fine silica	49

The above wettable powder is prepared as in Example 81.

60 This formulation is applied at the rate of 1½ pounds per 100 gallons in the first cover spray for control of apple scab and cedar-apple rust in an apple orchard. Good control of both diseases is obtained.

Example 83

	Percent
Cetyl pyridinium dimethyldithiocarbamate	20
A blend of long chain fatty amides	2
Xylene	78

70 The above emulsifiable composition is prepared by simple mixing of the mutually soluble components. When dispersed in water this composition forms a cationic emulsion.

75 This formulation is applied at the rate of 1 pint per

100 gallons to a grove of Bartlett pears as a preventive treatment for control of pear scab. Sprayed trees are protected from the disease while unsprayed trees are severely infected with scab.

Example 84

Percent

Dodecyl trimethylammonium dimethyldithiocarbamate	25
Attapulgite clay	75

The above wettable powder is prepared in the same manner as Example 81.

This formulation is applied at the rate of 1.5 pounds per 100 gallons to peach trees to prevent infection and development of scab on the growing fruit. No scab lesions are noted on peaches from the sprayed trees, whereas lesions are prevalent on unsprayed controls.

Example 85

Percent

Tetradecyl trimethylammonium dimethyldithiocarbamate	20
Diatomaceous silica	80

The above wettable powder is prepared in the same manner as Example 81.

This formulation is applied at the rate of 2 pounds per 100 gallons to a pear orchard 48 hours after a scab infection period. Developing scab lesions on the leaves are eradicated and the trees protected from early re-infection by scab and also from sooty blotch disease.

Example 86

Percent

Cetyl dimethyl benzylammonium dimethyldithiocarbamate	10
Attapulgite clay	40
Pyrophyllite	50

The above dusting composition is prepared by mixing the active material with the minor diluent and grinding to an average agglomerate size of less than 50 microns, then blending this mix with the major diluent.

This composition is applied by dust blower to a home planting of dwarf apple trees for protection from apple scab, Brooks spot, and sooty blotch. Good control of all three diseases is obtained.

Example 87

Percent

Tetradecyl trimethylammonium diethyldithiocarbamate	50
Synthetic fine silica	50

The above wettable powder is prepared in the same manner as Example 81.

This composition is included at a rate of 3/4 pounds per 100 gallons in the shuck-fall spray in a cherry orchard for control of cherry leaf spot. Excellent control of the disease is obtained on the treated trees.

Example 88

Percent

Stearyl dimethyl benzylammonium diethyldithiocarbamate	50
Synthetic fine calcium silicate (neutral)	50

The above wettable powder is prepared in the same manner as Example 81.

This composition is applied at the rate of 1 pound per 100 gallons to an interplanted apple and peach orchard for the control of apple scab, peach scab, sooty blotch, and frog-eye leaf spot. Good control of both apple and peach diseases results.

Example 89

Percent

Cetyl pyridinium ethylenebisdithiocarbamate	20
Mixed long chain fatty amides	2
Xylene	78 75

The above emulsifiable oil is prepared in the same manner as Example 83.

This composition is applied to a planting of crab apple tree for protection from attack by apple scab. A rate of 1 pint per acre is used, and good protection is afforded from the fungus disease.

Example 90

Percent

Cetyl dimethyl benzylammonium ethylenebisdithiocarbamate	10
Attapulgite clay	30
Micaceous talc	60

The above dust is prepared by first blending and grinding the active component with the minor diluent until substantially all agglomerates are reduced to below 50 microns, then blending this mix with the major diluent.

A row of grapes is dusted just prior to bloom with this composition at the rate of 10 pounds per acre for protection against black rot. Repetition of the treatment immediately after bloom and at two weeks after bloom gives good control of the disease.

Example 91

Percent

Cetyl trimethylammonium ethylenebisdithiocarbamate	25
Attapulgite clay	75

The above wettable powder is prepared in the same manner as Example 81.

An apple orchard is sprayed 24 hours after a scab infection period with this composition at a rate of 1 pound per 100 gallons. Scab lesions which have begun are eradicated from the leaves and the trees are thus protected from this disease.

The compounds above numbered 1 to 79 can be formulated in each of the ways shown. Thus in each of the Examples 80 to 91 above, the quaternary ammonium dithiocarbamate there named can be replaced with an equal weight of the quaternary ammonium dithiocarbamate of Examples 1 to 79 and applied as shown.

This application is a continuation-in-part of copending application Serial No. 779,559, filed December 11, 1958, now abandoned.

The claims are:

1. A method for controlling plant pathogenic fungi comprising applying to a plant a fungicidally effective amount of:

in which:

55 Q is selected from the group consisting of

and

65 R₁ is an alkyl hydrocarbon group of 10 to 18 carbons R₂ is selected from the group consisting of hydrogen and an alkyl hydrocarbon group of less than 5 carbons, R₃ is an alkyl hydrocarbon group of less than 5 carbons, R₄ is selected from the group consisting of an alkyl and aralkyl hydrocarbon group of less than 13 carbons, and, when R₆, N and R₅ taken together comprise a pyridinium group, a merged constituent of such pyridinium group,

R₅ is selected from the group consisting of methyl and ethyl,

R_6 is selected from the group consisting of methyl, ethyl, and, when R_4 , N, and R_5 taken together comprise a pyridinium group, a merged constituent of such pyridinium group.

2. A method for controlling plant pathogenic fungi comprising applying to a plant a fungicidally effective amount of cetyl pyridinium dimethyldithiocarbamate.

3. A method for controlling plant pathogenic fungi comprising applying to a plant a fungicidally effective amount of cetyl pyridinium ethylenebisdithiocarbamate.

4. A method for controlling plant pathogenic fungi comprising applying to a plant a fungicidally effective amount of cetyl pyridinium methyldithiocarbamate.

5. A method for controlling plant pathogenic fungi comprising applying to a plant a fungicidally effective amount of cetyl pyridinium diethylidithiocarbamate.

6. A fungicidal formulation containing 5 to 90% of the compound described in claim 1, the balance consisting essentially of a finely divided, free-flowing, inert extender and containing additionally a surface-active agent.
